UNITED STATES PATENT OFFICE.

HERBERT ALFRED HUMPHREY, OF LONDON, ENGLAND, ASSIGNOR TO HUMPHREY GAS PUMP COMPANY, A CORPORATION OF NEW YORK.

UTILIZING AN EXPANSIVE FORCE IN THE MOVEMENT OF LIQUID.

1,272,269.

Specification of Letters Patent.

Patented July 9, 1918.

Application filed April 30, 1912, Serial No. 694,287. Renewed December 8, 1917. Serial No. 206,326.

To all whom it may concern:

Be it known that I, HERBERT ALFRED HUMPHREY, a subject of the King of Great Britain, residing in London, England, have 5 invented a new and useful Improvement in Utilizing an Expansive Force in the Movement of Liquid, of which the following is a specification.

My invention relates to improvements in 10 the art of utilizing an expansive force, in which liquid is moved by the expansive force of an ignited compressed combustible charge.

The present invention comprises the use 15 of a plurality of solid or rigid masses or pistons operating in connection with the liquid, or a fluid and the expansible charges. The charges are preferably expanded between the said piston, or at least expanding 20 simultaneously against said pistons. The several pistons may be composite or differential.

My invention comprises also means for 25 controlling and utilizing compressed elastic cushions and also for controlling certain inlets and exits by said pistons. My invention also comprises the balancing or equalizing of the forces due to momentum or inertia, all of which will be fully described herein.

30 Referring to the drawings, which illustrate merely by way of example, suitable means for effecting my invention—

Figure 1 is a vertical section of a pump having two pistons working in the combustion chamber.

Fig. 2 is a similar view of a modified form showing means for securing uniform action of the two pistons.

Fig. 3 is a vertical section showing two 40 pistons working in parallel but having a common combustion chamber.

Fig. 4 is a vertical section of further modifications especially in piston and air chamber arrangements.

Fig. 5 is a detail in part section of a modification in the solid piston.

Fig. 6 is a vertical section of further modifications in piston and air chamber arrangements.

50 Fig. 7 is a horizontal section of a modified form of the device shown in Fig. 1.

Fig. 8 is a similar view of a modified form of the device shown in Fig. 4.

Fig. 9 is a sectional detail indicating the 55 arrangement for three piston devices.

Fig. 10 is a similar view indicating the arrangement for four piston devices.

Similar numerals refer to similar parts throughout the several views.

In Fig. 1, 1 is the combustion chamber in 60 which move two pistons 2 and 3. The position of these pistons is shown at the end of their outstrokes from the center of the combustion chamber when they have compressed elastic cushions in the spaces 4 and 5. These 65 cushion spaces communicate with additional vessels for elastic fluid 6, 7, 8 and 9, arranged as shown and controllable by valves so that they can be shut off from the respective spaces with which they communicate. 70 The pistons are in this case shown as having extensions 10 and 11 moving in cylinders 12 and 13 respectively which are of smaller diameter than cylinder 1. The pistons are hollow and the ends turned away from the 75 combustion chamber are open to allow access of liquid so that the working pistons 2, 3, in the combustion chamber may be kept cool. Liquid to be raised or forced enters through pipes 14, 15, controlled by liquid inlet valves 80 16, 17, and liquid reciprocates in the two branch pipes 18, 19, which join into one pipe 20 leading to the place where liquid is delivered.

Fitted in the combustion chamber 1 are 85 exhaust valves 21, 22, and in the exhaust pipe there is a non-return valve 23. There is also a scavenging valve for air, 24, and a valve for combustible mixture 25. The apparatus when working on a 4-stroke cycle 90 operates as follows:

In the combustion chamber, we may assume that the two pistons 2, 3, are close to the center of the chamber and that there is compressed between them a combustible 95 charge which is ignited to give the power stroke. When expansion has reached atmospheric pressure exhaust valves 21 and 22 open and the scavenging air valve 24 permits air to enter as the pistons continue 100 their movement. This air being cool, and therefore denser than the hot products of combustion, may tend to lie along the bottom of the cylinder. During the first return stroke of the pistons exhaust gases are 105 driven out through valves 21, 22 and past valve 23 so that when the valves are seated an elastic cushion consisting mostly of scavenging air will be compressed between the pistons. The energy of expansion of this 110

cushion drives the pistons apart and gives the second outward stroke during the latter portion of which fresh combustible mixture is drawn in through valve 25. Then 5 follows the second return stroke in which the fresh combustible charge is compressed. The exhaust, scavenging air, and gas valves may be interlocked in any suitable manner, as described in several of my previous specifications, so that on the first outstroke valves 10 21, 22 and 24 open but are locked shut on the second outstroke, whereas valve 25 is locked shut on the first outstroke but allowed to open on the second outstroke. Referring now to the movement of the liquid column during the cycle, on the first outstroke liquid is propelled along pipes 18, 19 and 20 the valves 16, 17, being shut until the diminution of pressure on the top side 15 of these valves due to the momentum of the moving liquid causes the valves to open and fresh liquid to be taken in. The return of the reciprocating masses under the head or pressure to which the liquid has been raised 20 or forced, aided it may be, by the expansion of the elastic cushions compressed, or by the continuation of such expansion, produces the first return stroke. On the second outstroke which occurs under the influence of the expansion 25 of the elastic cushion compressed in chamber 1 the liquid may move in pipes 18, 19 and 20 without taking in fresh liquid but energy is thereby stored to produce or assist in producing the second return stroke. 30 The function of the elastic cushions in 4, 5, 6, 7, 8 and 9 is to control the movement of the pistons 2, 3, in the desired manner and to store some of the energy which produces the return movements of the pistons, and 35 the advantage of having auxiliary cushions arises from the fact that the energy stored for a given movement of the pistons may be varied by varying the capacity of the cushions. These cushions may be normally at 40 a pressure differing from atmospheric pressure and their range of pressure changes may be adapted to suit varying conditions. 45 In Fig. 2 the corresponding parts are numbered to agree with Fig. 1 and the chief 50 difference is that instead of differential solid pistons, the two pistons 2, 3, which reciprocate in the combustion chamber are attached by rods to pistons 26, 27, for compressing elastic cushions in spaces 28, 29. 55 The piston rods on the respective sets of pistons are continued to crossheads 30, 31, to which are linked rods 32, 33, which in their turn are pivoted to the ends of a rocking arm 34 oscillating about a center shaft 60 35. By means of this arrangement the travel of the two pistons 2 and 3 may have fixed ratios and in the case shown their movements will be equal no matter what the length of the stroke. Moreover, the additional moving parts introduced afford a

ready means for operating any of the valves or other controlling devices and for timing the ignition.

In the inner ends of the cylinders in which pistons 26, 27 reciprocate are shown 70 openings 36, 37, for the admission and rejection of air, so that elastic cushions are in such case only formed in the spaces 28, 29. By closing up these openings energy may be stored by creating a partial vacuum which 75 would assist cushions 28, 29 in producing a return stroke.

In Fig. 3 the two pistons 2, 3 instead of working in the same cylinder reciprocate in two separate cylinders 38, 39, which communicate at the top through the passage 40 so that on the power stroke when combustion occurs both pistons move downward together. Attached to the two pistons are two other pistons 41, 42, joined by distance pieces 80 43, 44 respectively. The distance pieces are not of sufficient length to prevent the upper pistons 2 and 3 working on surfaces of the walls which are not wet, but the lower pistons 41, 42, will sweep away the liquid 85 from the walls of the chambers and any liquid which may escape past the lower pistons may find an outlet through non-return valve 45, a liquid seal being put on this valve. Admission valves 24 and exhaust 90 valves 21 are fitted around the respective cylinders at suitable heights therein, and a non-return valve 23 prevents exhaust gases from returning to the combustion chamber. In the position of the pistons shown in the 95 Fig. 3 there is a compressed combustible charge in the tops of the cylinders and in the space 40 between them, and on ignition and expansion the pistons are driven downward forcing the liquid that is below the pistons 100 41, 42, downward and outward into the play pipe 46 so as to start the oscillation of the liquid column therein. When the top of the piston 3 passes the level of the ports 47 the valves 21 will be held closed on their seats 105 by the pressure of the gases in the cylinder but when expansion has reached atmospheric pressure valves 21 will open either by their own springs or by suction and remain open during the further downward movements of the pistons and the following upward movement until the top of piston 3 again closes the ports 47. During the latter part of the downward movement after the exhaust gases 110 have expanded to about atmospheric pressure the further movement of the pistons draws in a charge of combustible mixture through valves 24 and on the return movement of the pistons exhaust gases are driven out through valves 21 until the rising of the piston 3 closes ports 47. Further movement 115 compresses the charge which will now be situated above the pistons and the increase of pressure acting upon valves 21, the heads of which have a piston fit in circular recesses, 120 125 130

5 forces these valves onto their seats. Valves 24 close under the action of their springs when suction ceased. In order to utilize the momentum of the outwardly propelled column of liquid from the play pipe to draw in more liquid through liquid inlet valves 16, 17, the motion of the pistons is arrested by the compression of elastic fluid in the chamber 48 and the pistons brought to rest 10 while the liquid column is still moving outwardly.

15 On the right hand side of cylinder 48 is shown a by-pass 49 opening into the cylinder 48 by ports 50, 51, so that the elastic fluid below piston 52 which is attached by rods 53 to the pistons 2 and 3 may be forced through port 51 and by-pass 49 to the top side of piston 52 as the latter moves downward. When, however port 51 is passed the 20 only escape for elastic fluid from below the piston 51 is through port 54 and valve 55. By adjusting the extent to which valve 55 is closed the further downward movement of piston 52 may be arrested as desired but 25 in any case if its movement extends beyond port 54 it will compress the remaining elastic fluid below piston 52. The upward movement of the pistons may be brought about by the return stroke of the liquid column in 30 the play pipe assisted in some cases by the expansion of the elastic fluid compressed below port 54 and it may be by fresh liquid flowing in under pressure when the level of the liquid supply is suitable.

35 A modification in which pistons 2 and 3 which reciprocate in a common combustion chamber 1 and serve the functions of opening and closing ports for the admission and exhaust of the elastic fluids, is shown in Fig. 40 4. Thus, a ring of exhaust ports in the cylinder walls of chamber 1 communicate with an exhaust pipe 58. Another ring of ports communicates with the scavenging air pipe 59 and a third ring of ports communicates 45 with the combustible gas supply pipe 60. The reciprocation of piston 61 which forms part of the piston 2 causes the intake of combustible gas through valve 62 and its delivery into the storage vessel 63. Similarly, the reciprocation of piston 64 causes the intake of scavenging air through the inlet valve 65 and its delivery into the storage vessel 66. There are two other pistons 67, 68, connected respectively to pistons 2 55 and 3 which act upon the liquid in contact with their outer faces. On their inner faces they are in contact with air which is alternately drawn into and exhausted from the cylinders in which they work. This air may 60 be utilized for any useful purpose and if the inner ends of the cylinders are closed a partial vacuum can be produced to assist the elastic cushions constituted in the spaces 69, 70, in producing an inward movement 65 of the pistons. The apparatus works on the

2-stroke cycle as follows:—On ignition of the compressed combustible charge contained between the two pistons 2 and 3 the pistons are driven apart so that toward the latter part of the outstroke the respective ports are 70 uncovered by the pistons and exhaust gases are blown out of the combustion chamber by the entrance under pressure of scavenging air and then of a mixture of air and gas in the well known manner of the Oechel- 75 hauser cycle. The inward stroke may be produced entirely by means of energy stored in elastic cushions such as the gas and air entrapped in the spaces 69, 70, when the respective pistons close the outlets to the reservoirs 63 and 66, but in the present case these cushions are shown comparatively small to indicate that the energy for the return stroke which compresses the fresh combustible charge may be furnished by the 80 liquid in pipe 20 returning under the head or pressure against which it has been raised 85 or forced.

85 A useful modification in connection with the solid reciprocating pistons is shown in 90 Fig. 5, where piston 61 is the pump piston which takes in and delivers combustible gas to the reservoir 63 and so to the combustion chamber, but in this case the delivery of the gas is through channels 73 between the working face of piston 61 and ports on the periphery and close to the face of piston 2 which can register with ports 74 for blowing in the gas. Thus, in the position shown gas is compressed in reservoir 63 and space 69 95 and can pass freely through the channels 73 and ports 74 into the combustion chamber 1. If the scavenging air is compressed to a rather higher pressure in the reservoir 66 as compared with the pressure of the gas in 100 63 there need be no delivery of gas into pipe 59 when the openings in the piston pass the scavenging air ports.

105 In Fig. 6 there is shown a modification in which there need be no reciprocating mass 110 of liquid returning toward the combustion chamber to compress a fresh combustible charge, for in this case there may be provided a sufficient store of energy in the elastic cushions to produce the return movement 115 of the pistons and to compress the charge in the combustion chamber previous to ignition. It is then possible to introduce non-return valves 75, 76, so that the liquid acted upon by pistons 67, 68, having been forced 120 through these valves, cannot return. In this case there are shown close to the last mentioned valves air vessels 77, 78 from which liquid may flow more or less continuously in one direction through the pipes 18, 125 19, 20. As before, the pistons 2, 61, 67, are rigidly attached and reciprocated together as a liquid raising or forcing unit, but the pistons 61 and 2 are constructed with an internal cylinder as shown to receive a sta- 130

tionary plunger 79. Through the plunger are a number of passages 80 leading to the vessels for elastic fluid 6 and 7, so that elastic fluid compressed in the space 81 can pass through a series of passages 80 into the vessels 6 and 7 as the piston 2 moves to the left, thereby storing the energy required for producing the return stroke. Some of the energy may also be stored in the space 69 and there are many ways of arranging suitable elastic cushions which may be made adjustable in capacity. There may for instance be an air cushion placed in communication with the liquid between the liquid inlet valves 16 and the delivery valves 75. In the example shown in Fig. 6 both the liquid inlet valves 16, 17, and the liquid discharge valves 75, 76, are shown communicating with air vessels so that the inertia of the moving mass of liquid may be reduced to a minimum. As in Fig. 4, there are internal passages 82, 83, in the reciprocating pistons for conveying liquid to and from the piston head 2 so as to cool the latter by natural circulation.

When pumps constructed according to the invention are to be used for ship propulsion it is of great importance that there should be no unbalanced forces due to momentum or inertia of the reciprocating or moving parts.

Figs. 7 and 8 show diagrammatically how the various parts of the apparatus may be arranged so as to produce a complete balance of such forces in all directions. In Fig. 7 there are two inlet pipes for liquid 14, 15, and two delivery pipes for liquid 20, 20^a, arranged symmetrically, and the pipes for liquid 18, 19, are duplicated at 18^a, 19^a. The flow of liquid through 14, 15, respectively may at all parts of the cycle be the same in velocity and likewise the delivery of liquid at 20, 20^a, respectively may through all parts of the cycle be at the same velocity. In Fig. 7 the liquid in the pipes 18, 19, 20 reciprocates, but in Fig. 8 there is shown a symmetrical arrangement of apparatus in which the liquid moves only in one direction in the pipes 18, 19, and 18^a, 19^a. In this case air vessels 77, 78, on the one side of the apparatus may be balanced by other air vessels 77^a, 78^a, and all four air vessels may be made of such a size that there is approximately constant flow on liquid from them. As Fig. 7 corresponds with Fig. 1 and Fig. 8 corresponds with Fig. 6 except for the additional connections for liquid which are used to produce the balance of forces, the general cycles of operation need not be described.

When there are three pistons acted upon by the expanding combustible gases they may be arranged symmetrically as shown in Fig. 9. In such case it is generally desirable that the three pistons should perform similar functions. When the number of pistons is increased to four they may be arranged symmetrically as shown in Fig. 10, and in

this case one pair of pistons which are co-axial may differ in function from the other pair of pistons and yet there may be a complete balance of forces. Thus pistons 87, 84, may act upon liquid and pistons 85, 86, may act upon elastic fluid and may serve the purpose of supplying scavenging air and the constituents of the combustible mixture to the combustion chamber. One set of co-axial pistons may differ in diameter from the other set of co-axial pistons, and it is generally desirable that the ignition should be timed or operated by the movements of those pistons which act upon liquid. If all the four pistons of Fig. 10 are used for compressing elastic fluid two of the pistons may be used to deliver elastic fluid for external use and the other two pistons for supplying scavenging air and combustible mixture to the combustion chamber.

What I claim is:—

1. The combination of an expansion chamber, play pipes for the reciprocation of liquid connected therewith and a plurality of pistons having their ends operating in the expansion chamber with their other ends acting directly upon the liquid.

2. The combination of an expansion chamber, pipes for the reciprocation of liquid connected therewith, a plurality of pistons each having an end operating in the expansion chamber, the other ends acting directly upon the liquid, and means for forming elastic cushions adapted to store energy on the power stroke and to give up energy in connection with the return stroke of the pistons.

3. An expansion chamber, a plurality of pistons operating therein, a play pipe for the reciprocation of liquid, means whereby the pistons are actuated by a primary medium to operate directly against the liquid and means whereby the momentum of the liquid column may be utilized to introduce fresh liquid.

4. An expansion chamber, a plurality of pistons operating therein, a play pipe for liquid, means whereby the pistons are actuated by a primary medium in the expansion chamber to operate directly against the liquid to actuate the same, and whereby the liquid on its return stroke operates directly upon the pistons to actuate the same.

5. An expansion chamber, a plurality of pistons operating therein, a play pipe for liquid of sufficient bulk and path of travel to acquire useful momentum, means whereby the pistons are actuated by a primary medium to operate directly against the liquid, and means for forming elastic cushions for storing and imparting energy during the different cycles of operation.

6. An expansion chamber, a plurality of pistons operating therein, a play pipe for liquid of sufficient bulk and path of travel to acquire useful momentum, means whereby

the pistons are actuated by a primary medium in the expansion chamber to operate directly against the liquid, means for forming elastic cushions for storing and imparting energy during the different cycles of operation, and means for rendering ineffective one or more of the said elastic cushions.

7. The combination of an expansion chamber, pipes for the reciprocation of liquid, a plurality of differential pistons each having an end operating in the expansion chamber with the other end acting directly upon the liquid to be forced.

8. The combination of an expansion chamber, pipes connected therewith for the movement of liquid of sufficient bulk and path of travel to acquire useful momentum, a plurality of pistons each having an end operating in the expansion chamber with the other end acting directly upon the liquid, the expansion chamber provided with inlet and discharge valves, and means whereby the power stroke serves to draw in scavenging air and also a fresh expansible charge.

9. The combination of an expansion chamber, pipes connected therewith for the movement of liquid of sufficient bulk and path of travel to acquire useful momentum, a plurality of pistons each having an end operating in the expansion chamber with the other end acting directly upon the liquid, the expansion chamber provided with inlet and discharge valves, means for drawing in scavenging air upon the power stroke and also a fresh expansible charge, and means whereby the return stroke of the liquid acts upon the piston to compress the charge.

10. The combination of an expansion chamber, a play pipe for the movement of liquid connected therewith and a plurality of pistons each having an end operating in the expansion chamber with the other end acting directly upon the liquid to be forced, means whereby the movement of the liquid in the outstroke causes the introduction of fresh liquid into the play pipe.

11. The combination of an expansion chamber, pipes for the movement of liquid connected therewith and a plurality of pistons having their power ends operating in the expansion chamber with their pumping ends acting directly upon the liquid to be forced, said pistons being hollow with their pumping ends open to the liquid.

12. The combination of an expansion chamber, pump cylinders and a play pipe for liquid of sufficient bulk and path of travel to acquire useful momentum, a plurality of pistons operating in the expansion

chamber having extensions operating in the cylinders and adapted to operate directly upon the liquid in the play pipe.

13. The combination of an expansion chamber, pump cylinders and a play pipe for liquid of sufficient bulk and path of travel to acquire useful momentum, a plurality of pistons operating in the expansion chamber having extensions operating in the cylinders and adapted to operate directly upon the liquid in the play pipe, the cylinders provided with intake and discharge ports for air and gas adapted to be controlled by the pistons.

14. The combination of an expansion chamber, pump cylinders and a play pipe for liquid of sufficient bulk and path of travel to acquire useful momentum, a plurality of pistons operating in the expansion chamber having extensions operating in the cylinders and adapted to operate directly upon the liquid in the play pipe, the cylinders provided with intake and discharge ports for air and gas adapted to be controlled by the pistons, and means whereby air is trapped and compressed in said cylinder and whereby the compressed air is utilized to deliver at the proper point in the expansion chamber and at the desired moment scavenging air and gas.

15. The combination of an expansion chamber, pump cylinders and a play pipe connected therewith, a plurality of pistons operating in the expansion chamber having extensions operating in the cylinders and adapted to operate directly upon the liquid in the play pipe, the cylinders provided with intake and discharge ports for air and gas adapted to be controlled by the pistons, and means for trapping and compressing air between the pistons and cylinder walls to blow out the exhaust gases.

16. The combination of an expansion chamber, pump cylinders and a play pipe connected therewith, a plurality of pistons operating in the expansion chamber having extensions operating in the cylinders and adapted to operate directly upon the liquid in the play pipe, the cylinders provided with intake and discharge ports for air and gas adapted to be controlled by the pistons, and means for trapping and compressing air between the pistons and the cylinder walls and utilizing said compressed air for entraining said combustible mixture.

HERBERT ALFRED HUMPHREY.
